UNITED STATES PATENT OFFICE

147,250

DESIGN FOR A SHOE OR SIMILAR ARTICLE

Evelyn Z. Lipare, New York, N. Y.

Application June 14, 1947, Serial No. 139,689

Term of patent 3½ years

(Cl. D7—7)

To all whom it may concern:

Be it known that I, Evelyn Z. Lipare, a citizen of the United States of America, residing in New York, county of New York, and State of New York, have invented a new, original, and ornamental Design for a Shoe or Similar Article, of which the following is a specification, reference being had to the accompanying drawing, forming part thereof.

The figure on the drawing is a front perspective view of a shoe or similar article showing my new design, the opposite side presenting substantially the same appearance as the side shown.

I claim:

The ornamental design for a shoe or similar article, substantially as shown and described.
EVELYN Z. LIPARE.
